(57) **CLAIM**

We claim the ornamental design for a model vehicle pivoting axle carrier holder, as shown and described.

DESCRIPTION

FIG. 1 is an upper, left, front perspective view of a model vehicle pivoting axle carrier holder;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an upper, left, front perspective environmental use view of the model vehicle pivoting axle carrier holder.

In the drawings, the broken line showing of features of the model vehicle pivoting axle carrier holder illustrate portions of the model vehicle pivoting axle carrier holder that form no part of the claimed design; whereas, the broken line showing of the environmental use view depicts environmental subject matter and is provided for the purposes of illustrating environmental use structure and context and also forms no part of the claimed design.

In the drawings, only the first embodiment of the model vehicle pivoting axle carrier holder is shown. The second embodiment of the claimed design is a right model vehicle pivoting axle carrier holder which is a mirror image of the left model vehicle pivoting axle carrier holder disclosed in the first embodiment.
